UNITED STATES PATENT OFFICE.

JOHN McLAREN, OF NEW YORK, N. Y.

VALVE-GEAR FOR ENGINES.

SPECIFICATION forming part of Letters Patent No. 409,058, dated August 13, 1889.

Application filed February 28, 1889. Serial No. 301,508. (No model.)

To all whom it may concern.

Be it known that I, JOHN McLAREN, a citizen of the United States, residing at the city of New York, county and State of New York, 5 have invented new and useful Improvements in Valve-Gear for Steam-Engines, of which the following is a specification.

This invention relates to a novel mechanism for tripping the steam-valves of an engine by the action of the governor, the construction of said mechanism being pointed out in the following specification and claim, and illustrated in the accompanying drawings, in which—

15 Figure 1 is a side view of the tripping mechanism. Fig. 2 is a front view of the same. Fig. 3 is a longitudinal section in the plane x x , Fig. 2. Fig. 4 is a vertical section in the plane y y , Fig. 3. Fig. 5 is a side elevation of a Corliss engine provided with my valve-gear, on a smaller scale than the previous figures. Fig. 6 is a plan or top view of the same. Fig. 7 is a longitudinal section of the steam-cylinder detached.

25 Similar letters indicate corresponding parts. In the drawings, the letter A designates the steam-cylinder, (shown in dotted lines in Figs. 1, 2, and 3,) which is provided with four valve-chambers B B' C C', Fig. 7, in which 30 move the valves b b' c c' , the valves b b' being the steam-valves and the valves c c' the exhaust-valves. An oscillating motion is imparted to these valves by means of an eccentric D on the crank-shaft E, Figs. 5 and 6, 35 which connects with a disk F, from which extend connecting-rods G to arm H, from which motion is transmitted to the stems d d' of the steam-valves b b' in the following manner: The arm H extends from a sleeve I, Fig. 40 1, which is loosely mounted on the bearings of the stem d. This sleeve carries a bracket J, which supports the movable tappet K, which, in the example shown in the drawings, is mounted on a pivot j, so that it can 45 swing from its active position (shown in full lines, Fig. 3) into its inactive position, (indicated in that figure in dotted lines.) A spring j' has a tendency to hold the tappet in its active position. On the valve-stem d is firmly 50 mounted a hub L, from which extends an arm

l , which is provided with a lip m, and from which the dashpot-rod M is suspended.

On the bearing of the valve-stem d is loosely mounted a cam N, which connects by a rod n, Fig. 5, with the governor O. When the engine runs at its normal speed, the cam N is retained in the position shown in Fig. 2, and as the sleeve I oscillates on the valve-stem the roller j³, mounted on the outer end of the tappet K, does not come in contact 60 with the cam N, and since said tappet on its upward movement acts upon the lip m of the arm l the valve-stem d is turned and the valve b is opened and kept open until the tappet returns to the position shown in Fig. 65 2. If the speed of the engine increases beyond its normal point, the cam N is turned in the direction of arrow 1, Fig. 2, the projection n² on said cam is brought into the path of the roller j³, and as soon as this roller 70 strikes against said projection the tappet K is thrown out of its active position, the arm l is released, the dashpot-rod M drops down, and the valve b is closed.

What I claim as new, and desire to secure 75 by Letters Patent, is—

The combination, with the valve b and its stem d, mounted in a suitable bearing, of the sleeve I, loosely mounted on the bearing and carrying the valve-tripping tappet K, which 80 is pivoted intermediate its ends, a spring j' for normally holding the tappet in its active position, means, substantially as described, for oscillating the sleeve, the hub L, fixed on the valve-stem and having the projecting arm 85 l, against which one end of the tappet engages, the cam N, loosely mounted on the valve-stem bearing for acting on the opposite end of the tappet, the governor O, and connections between said governor and the 90 cam for rotating the latter when the speed of the governor increases beyond a certain limit.

In testimony whereof I have hereunto set my hand and seal in the presence of two subscribing witnesses.

JOHN McLAREN. [L. S.]
